GASOLINE ECONOMIZER FOR COMBUSTION ENGINES

François Casanova, Nice, France

Application March 25, 1939, Serial No. 264,270
In France November 4, 1938

3 Claims. (Cl. 123—124)

The present invention refers to an economizer for gasoline or similar fuel, adapted to be placed between the carburetor and the intake manifold of an internal combustion engine for substituting an intake of pure air for the intake of the fuel mixture, every time the engine is idling or is driven by the apparatus or the machine it normally actuates, as for instance, in the case of a motor vehicle, every time said vehicle is braked or runs down a hill, and the like.

In other words the invention is particularly useful for coasting as it breaks the vacuum and admits air to economize on the fuel, but when the vehicle is running normally no air is admitted but instead the usual fuel mixture.

This economizer differentiates from similar apparatus of known types by virtue of a special device including a sleeve which is perforated with holes or apertures in the wall thereof and is interposed between the conventional manifold admitting the fuel gases to the engine and the carburetor. Said sleeve has on the one hand, an interiorly located throttle valve capable of cutting off the supply of gaseous fuel mixture normally passing between said carburetor and the engine, and, on the other hand an obturating or closing member connected to, or rigid with, the throttle valve and effective to uncover said apertures when the throttle valve is closed and cover the same when said valve is open. This throttle valve and the obturator are both controlled by a vacuum pump actuated by any rotating member of the vehicle, for controlling in opposition to the action of a returning spring, said throttle valve every time, during the operation of the engine, the driver ceases to press on the accelerator pedal. At this moment the intake of the fuel mixture is thus cut off by the throttle valve of the sleeve, the intake of pure air is open and, moreover, there is no need for the driver to act on the accelerator pedal for maintaining the idling of the engine since the intake of the fuel mixture is automatically re-established as soon as the partial vacuum produced by the pump falls below a certain value.

Another feature of the invention consists in actuating by means of the pedal controlling the normal throttle valve of the carburetor, the member actuating the partial vacuum pump.

The features of the invention will be described in greater detail with reference to the forms of construction illustrated in the accompanying drawings, in which:

Fig. 1 is a vertical section of the economizer in the position corresponding to the total cutting off of the fuel.

Fig. 2 is a diagrammatic view, with parts in vertical section, of the arrangement according to the invention.

Fig. 3 is a plan view of the slide valve controlling the air controlled valve, of which

Fig. 4 is a view in vertical section.

Fig. 5 is a plan view of a vacuum pump.

Fig. 6 is a vertical section of a modification to the economizer shown in Fig. 1 in position for the passage of the fuel.

Fig. 7 is a similar section corresponding to the total cutting off of the fuel mixture.

Fig. 8 is a horizontal section made according to line III—III of Fig. 2.

The member 1 is a stationary sleeve adapted to be interposed between the flange of the carburetor 1a and the intake manifold 1b of the engine; arrows indicate the direction of flow of the fuel mixture (Fig. 1). In the sleeve 1, the throttle valve 3 controlling said flow is mounted on a transverse shaft 4 on which is secured a lever 6.

Said sleeve 1 comprises, on a plane face 12, one or more apertures 13 putting the intake manifold 1b of the engine in communication with the atmosphere. On the shaft 4 of the throttle valve is also secured a segment 14 which can uncover the apertures 13 when the throttle valve 3 is closed.

The control of lever 6 is effected by a rod 15 (Figs. 2 and 6) adjustably attached to the free end of a lever 16 the other end of which is pivotably mounted on an axle 17 rigid with a chamber 18 tightly closed on one side of a diaphragm 19, the middle portion of which is secured at 20 to the lever 16; the movements of said diaphragm therefore control those of the rod 15 and, consequently, of the lever 6, and of the segment 14 determining the opening or the closing of the apertures 13.

Said diaphragm 19 expands outwardly or inwardly according as the fluid-tight chamber 18 it closes is filled or emptied of air through the pipe 21 connected to a control valve 22 (Fig. 2) comprising a casing 23 containing two chambers 24 and 25 separated by a diaphragm 26 and by a calibrated capillary hole 33. The chamber 24 is connected through the pipe 21 to the intake manifold, and chamber 25, through the tube 28, with a slide valve 29. A flap-valve 30 moves in the casing 22 and abuts on seats 31; the tail of the valve is secured on the diaphragm 26.

When partial vacuum is exerted in the chamber 24, and in the chamber 25 through the calibrated capillary hole 33, the flap-valve 30 is pressed on its seat 31, the diaphragm 19 is in its normal position, lever 6 is attracted by spring 7 and the apertures 13 are closed by the segment 14.

The movements of the diaphragm 26 which determine the operation of the system are controlled by the movement of the slide 29 relatively to the air inlet hole 38 formed in one side 60 of the guide 35.

Said slide has a transverse channel 37; when this channel is in communication with tube 28, atmospheric pressure exists in chamber 25 of the valve. If the slide moves, chamber 25 is at the pressure of chamber 24 through the hole 33.

Finally, these alternations of pressure and partial vacuum in valve chamber 25 are functions of the position of the slide 29 in the guide 35; the latter is connected by a rod 39 to the means controlling the carburetor 1a through lever 5 operating the conventional carburetor throttle valve 3a, said means including the accelerator pedal 42 connected by a rod 43 to said valve 3a, while on said rod 39 is provided a clearance adjustable by means of the abutment 40 of a spring 41.

The operation of the economizer is as follows:

As long as the driver presses more or less on the accelerating pedal 42, the throttle valve 3a of the carburetor is more or less open (position shown in dot and dash lines in Fig. 2), the slide closes the air inlet to the conduit 28, the diaphragm 26 is subjected on both its faces to the same partial vacuum existing in the compartments 24 and 25 communicating through the aperture 33, the valve 30 is lowered and atmospheric pressure is created in the chamber 18; the diaphragm 26 is stationary, the throttle valve 3 open and the obturator 10 closed. When the driver ceases to press on the pedal 42 (position shown in full lines in Fig. 2), partial vacuum is created in chamber 24, the flap-valve 30 is pressed on its seat 31. When the accelerator pedal is completely at rest, the slide 29 is in the position shown in Fig. 3 in the guide 36 and air enters through 37, in the tube 28 and in chamber 25, pushing back the diaphragm 26, owing to the fact that partial vacuum exists in chamber 24 and atmospheric pressure in chamber 25. The flap-valve 30 is pressed on its seat 31 and the chamber 24 is connected to the chamber 18 through the pipe 21 so that vacuum is created behind the diaphragm 19 which attracts the rod 15; the apertures 13 are uncovered and the gas valve is closed. As soon as the accelerator is acted upon, the slide 29 moves, the inlet of air into chamber 25 is cut off, partial vacuum extends through the calibrated hole 33 of chamber 24 to chamber 25; the diaphragm 26 returns to the position of rest and the flap-valve 30 closes. The diaphragm 19 returns to normal position and the spring 7 restores the rod 15.

Instead of actuating the valve 22 by the partial vacuum of the engine, a suction pump 42 in connection with the chamber 18 (Fig. 5) can be provided which is set in action by a Cardan joint 43 through the medium of a friction disc 44 and a driving pulley 45. This pump can be slidably mounted on a support 46 secured to the vehicle frame 47 and connected to the control of the carburetor by a link-work 48. A suitable transmission sets the pump in action as soon as the accelerator is no longer pressed upon, so that the pump sucks only when it is necessary to run with economy.

Figs. 6 to 8 show another embodiment of the throttle valve 3, in which the lever 6 is connected to the spring 7 through the medium of a link 9 to which is secured the end of a flexible band 10, for instance a steel band, the other end of which is secured to the sleeve 1 at such a point that said band forms about the sleeve a loop extending over a large portion of its periphery.

In the position illustrated in Fig. 6, the throt-

tle valve 3 is wide open and the band 10 is pressed against the periphery of the sleeve, thus closing a series of air inlet holes 11 provided in the wall of said sleeve behind the throttle valve.

5 In the position illustrated in Fig. 7, the rod 15 actuated as stated by the partial vacuum pump 20, has closed the throttle valve 3 and uncovered the holes 11, this corresponding to economical running. The driver having ceased to press 10 on the pedal 42, the throttle valve 3a of the carburetor is in the position for slowing down, and the engine is only supplied with air under the action of the spring 7, so that there is no need for the driver to act on the accelerator for avoiding stoppage of the engine. The feeding of the engine thus remains automatically ensured with the minimum consumption of fuel.

What I claim is:

1. In connection with a carburetor having a conventional throttle valve and adapted for use on an internal combustion engine, a gasoline economizer including a stationary sleeve disposed between the throttle valve of the carburetor and the intake manifold of said engine, said sleeve being perforated by apertures in the side walls thereof, a throttle valve within said sleeve and an obturator exteriorly thereof connected to said latter valve so as to be movable therewith in order to open or close said apertures, spring means moving said rod to closed position of the obturator, a fluid tight casing having a diaphragm occupying an open side thereof, a rod connected to said diaphragm and controlling the movement of said obturator and the second throttle valve, a valve casing containing two spaced partitions separating the interior into three chambers, a pipe connecting one chamber with the interior of said fluid tight casing, a second pipe connecting the interior of the intake manifold with the second chamber, a slide valve for controlling the air intake, a third pipe connecting the interior of said slide valve with the third chamber, a flap valve movable in said first chamber to close alternately an aperture in the outer wall of said first chamber or an opposite aperture in one of said two partitions, a flexible diaphragm occupying an opening in the second of said partitions, means connecting said last mentioned diaphragm with said flap valve, and means causing the slide valve to open the air intake when the throttle valve of the carburetor is in the slowing down position.

2. A gasoline economizer according to claim 1, having an orifice in the second partition which supports the last mentioned flexible diaphragm and extends between the second and third chambers in the valve casing, and including linkwork connecting the slide valve to the conventional pedal controlling the throttle valve of the carburetor so that when said pedal is released the air intake controlled by the slide valve is open.

3. A gasoline economizer according to claim 1, in which the obturator includes a flexible blade forming an outer loop overlying the apertures in the sleeve and having one end secured to said sleeve, and an exterior operating lever connected to the other end of said sleeve, said economizer also having an orifice in the second partition which supports the last mentioned flexible diaphragm and extends between the second and third chambers in the valve casing, and including linkwork connecting the slide valve to the conventional pedal controlling the throttle valve of the carburetor so that when said pedal is released the air intake controlled by the slide valve is open.

FRANÇOIS CASANOVA,
